(57) **CLAIM**

The ornamental design for a soft cover firearm case convertible into a seat, as shown and described.

DESCRIPTION

FIG. 1 is a front elevational view of a soft cover firearm case convertible into a seat of the present invention. The undisclosed rear elevation being a mirror image.

FIG. 2 is a top plan view thereof.

FIG. 3 is a right side elevational view thereof. The undisclosed left side being a mirror image.

FIG. 4 is a front elevational view shown in alternate position. The undisclosed rear elevation being a mirror image.

FIG. 5 is a top plan view of FIG. 4.

FIG. 6 is a right side elevational view of FIG. 4. The undisclosed left side being a mirror image.

FIG. 7 is a plan view of FIG. 1 shown in an open position.

FIG. 8 is a plan view of FIG. 7 shown in an alternate position.

FIG. 9 is a plan view of FIG. 7 shown in an alternate position.

FIG. 10 is a plan view of FIG. 7 shown in an alternate position; and,

FIG. 11 is a plan view of FIG. 7 shown in an alternate position.

The broken lines shown are included for the purpose of illustrating unclaimed subject matter and forms no part of the claimed design.

1 Claim, 6 Drawing Sheets
